UNITED STATES PATENT OFFICE.

FRANK P. PORTELLO, OF PORTLAND, OREGON, ASSIGNOR OF ONE-THIRD TO J. B. OBERLE AND ONE-THIRD TO WM. A. HALL, BOTH OF PORTLAND, OREGON.

AUTOMATIC SWITCH CLOSER FOR TRACKS.

Application filed March 31, 1922. Serial No. 548,426.

To all whom it may concern:

Be it known that I, FRANK P. PORTELLO, a citizen of the United States of America, and resident of Portland, in the county of Multnomah, in the State of Oregon, have invented 5 certain new and useful Automatic Switch Closers for Tracks, of which the following is a specification, reference being had to the accompanying drawing.

10 My invention relates to systems of tracks, usually overhead tracks, adapted for distribution purposes in packing plants, for example. Such systems, as is well understood in the art, include a plurality and usually a 15 multitude of track mains and branches, that are each adapted to be operatively conjoined or broken at will through the instrumentality of switches, respectively placed, as occasion demands, at the junction of one of 20 said mains and a branch, the purpose being to afford means for transporting a loaded trolley along a main until a desired branch is reached, and then, by operation of the switch selected, shunting the trolley with 25 its load onto said branch. The provision of switches as described in such systems is found to answer all requirements satisfactorily so far as transportation and selection of destination are concerned. It has been 30 found in practice, however, that often an operator will fail to close a switch at the proper time, with the result of driving a trolley into a break or opening in the track and thereby of dropping the same, with certainty of serious loss of time in nearly every 35 instance, and with the additional possibility of loss by injury to the product as well as by personal injury to operatives, and damage to the plant or its equipment.

40 The object of my invention is to provide automatic and dependable means which will insure the closing of a switch whenever an oncoming trolley, in its travel towards it, reaches a determinate proximity to it.

45 What constitutes my invention will be hereinafter specified in detail and succinctly set forth in the appended claims.

In the accompanying drawing,

Figure I shows, by way of example only, 50 portions of a main track and of a branch track in top plan view, and shows in operative relationship thereto a main switch closed and a branch switch open. In connection with said tracks and switches is 55 illustrated in top plan view my invention

comprising a switch-closing element, and means, in operative disposition to the main track, for automatically closing the main switch every time a trolley requiring the closing of the switch approaches it.

60 Figure II is a view similar to Figure I showing the main switch open, the branch switch closed, and the oncoming trolley.

Figure III is a side elevation of the subject matter of Figure I. In this figure a 65 loaded trolley is shown in full lines substantially in the same position on the main track as that in which it is shown in Figure II, and in dotted lines in its switch-closing position on the track.

70 Figure IV is a section on the line IV—IV of Figure II, with unimportant portions in view broken away.

75 Figure V is a section on the line V—V of Figure I.

Referring to the numerals on the drawing, 1 indicates an example of a main track supporting beam, and 2 a branch track supporting beam. The beams 1 and 2, whose relationship one to another is substantially 80 identical with that of the respective tracks they carry, may be set at any relative angle desired, and, in service installation, they are multiplied indefinitely in number. 3 and 3^a indicate, respectively, two portions of a 85 main track rail that are supported on the beam 1 as by brackets 4 in any usual or any preferred manner, the two numerals employed to designate the rail being used to indicate the presence of a disconnection or 90 break between next adjacent portions of the rail. The main track rail 3^a is also adapted to make and break communication with a branch rail 5, through the mediation of a 95 curved track section 6. The rail 5 and the section 6 are separated by a break, disposed in convenient proximity to that which separates the portions of the main track rail.

The breaks between track rails, on adjacent main and branch tracks, for example 100 that between the rails 3 and 3^a and that between the rails 3^a and 6, are adapted to be closed by correlative actuated or compound switch-plates 7 and 8. Said switch-plates are pivotally mounted as upon a shelf 105 10 suspended, for example, from one end of the track portion 3^a and also, if need be, from a bracket 11 suitably supported from above by any preferred means.

110 The switch-plates 7 and 8 are denomi-

nated compound because the movement of one of them is made dependent upon that of the other. They are old in the art, but it is deemed necessary to specify herein that the 5 plate 7 is vibratory in a horizontal plane upon a vertical pivot stud 14 extending upwardly from the shelf 10. The plate 8 swings up and down on an axis 15 carried in lugs 16 upstanding from said shelf 10, and straddling the tail-piece 17 of the plate 7, which is free at all times to vibrate underneath the plate 8 and its axis 15. The plate 8 is provided with a tail-piece 18, by which it may be uplifted, as by a pull on the cord 19 10 depending through a hole 20 in the shelf 10.

The plate 7 carries a track-gap-filler 21, and the plate 8 a track-gap-filler 23, the former being adapted, when in the position of it shown in Figure II, to fill the break 20 between the rails 3 and 6, and the latter to fill, when in the position shown in Figure I, the break between the rails 3 and 3^a.

Comparison of Figures I and II will show that when either one of the track-gap-filters is open the other will be closed. 25 A suitable means to that end, and one by which said effect is ordinarily accomplished, consists in the correlative disposition of the tail-pieces 17 and 18 in respect to the stud 30 14 and the axis 15, and the correlative dispositions of a bent tongue 25 on the bottom of the plate 8 and an aperture 26 in the plate 7 into which the tongue 25 takes with snug fitting snub engagement between the 35 tongue and the surrounding aperture-defining wall.

In the foregoing specification of details, I have described only what is old and familiar in the art. My invention consists in the 40 application to mechanism of that description of means for insuring it against accident in use.

Let it be assumed, for example, that with such equipment only as that already described, the track rails and switches are in the several relative positions shown in Figure II, and that a trolley, indicated by the numeral 30, is approaching, in its line of travel, the end of the track rail 3. It is 45 obvious then that unless the switch-plate 8 be lowered in time to supply the track-gap-filler 23 to the end of the track rail 3 before the trolley reaches it, the trolley and its load 31—say for example of hundreds 50 of pounds weight—will fall from the track. It has been, therefore, the duty of operatives hitherto to attend always to the proper closing of the switches. It often happens, nevertheless, that an operative will neglect 55 his said duty with consequence that are always attended with some loss, and which are at times disastrous to life or limb.

My invention consists in the substitution 60 of mechanical means for human agency in closing the switches, whereby the closing 65

thereof is made automatically effective every time a trolley 30 reaches a point along a track adjacent to one at which a switch is located.

In present preferred form of embodiment, 70 my invention comprises a finger 35 that is carried on an actuating member. The free end of the finger is provided with a downwardly bent tip 37, which, by the longitudinal movement of the finger, is caused to engage the switch-plate 8 to which it is appropriated, with the effect of overbalancing it upon its axis 15 and causing it to drop by gravity. The same effect may be accomplished, as indicated in Figure VI, by 80 imparting, through the same movement of the actuating member, vibratory instead of longitudinal motion to the finger 35.

The actuating member is pivotally secured at one end, as indicated at 39, to the 85 beam 1. From its pivotal support 39, the said member extends substantially at right angles in an arm 40, from whose free end depends a rigid section 41, beyond which the member extends in a horizontal plane 90 in the form of a bow 42. The bow 42 is disposed in a horizontal plane substantially parallel to and preferably elevated a little above the tread of the track on which the trolley 30 travels. The disposition of the 95 bow 42 relatively to said track and trolley is such that the trolley, in order to pass along the track beyond the bow, must of necessity engage the bow and force it aside. The result is to cause the actuating member 100 to turn slightly upon its pivot 39, as indicated in dotted lines in Figure I, and thereby, through movement of its terminal upstanding arm 43, to actuate the finger 35, so as to cause the switch-plate 8 to turn 105 upon its axis 15 and to drop its track-gap-filler 23 into place to close with safety the break in the track.

The finger is guided for its own support and for that of the free end of the actuating member as by a guide loop 44 fastened to the bottom of the beam 1. A tensile spring 45 secured at one end to the beam 1 and at the other to the arm 43 serves to maintain a yielding normal relationship between the 110 track and the bow 42. The finger 35 may be threaded at its end next to the arm 43 for the accommodation on opposite sides of said arm of nuts 46 and 47 by which it may be made adjustable longitudinally in respect 115 to its connection with the arm 43.

The operation of my invention having been already described in the preceding specification,

What I claim is:

1. The combination with a series of inter-communicable tracks having breaks between, of switches for closing said breaks, and automatic means for operating said switches, respectively, said means comprising a mov- 120

able actuating member in operative communication with a track, and with a switch respectively, but separate from each other.

2. The combination with a series of inter-
5 communicable tracks having breaks be-
tween, of drop-closing switches for closing
said breaks, and an automatic switch clos-
ing member in operative communication
with the track and with each switch, re-
10 spectively.

3. The combination with a series of inter-
communicable tracks having breaks between
of switches for closing said breaks, and auto-
-

matic means for operating said switches,
respectively, said means comprising a mov-
able actuating member having a bow in
operative proximity to a track, and carrying
and operatively adjustable switch-engaging
finger.

In testimony whereof, I have hereunto 20
set my hand in the presence of two sub-
scribing witnesses.

FRANK P. PORTELLO.
